UNITED STATES PATENT OFFICE.

RUDOLPH COOPERSMITH, OF MONTREAL, QUEBEC, CANADA, ASSIGNOR OF ONE-HALF
TO ABRAHAM RUCHE, OF PHILADELPHIA, PENNSYLVANIA.

FOLDING BED.

Application filed November 8, 1920. Serial No. 422,706.

To all whom it may concern:

Be it known that I, RUDOLPH COOPERSMITH, a citizen of the United States of America, and resident of the city of Montreal, in the Province of Quebec, and Dominion of Canada, have invented certain new and useful Improvements in Folding Beds, of which the following is a full, clear, and exact description.

10 This invention relates to improvements in folding beds, and the object of the invention is to provide a bed of simple and durable construction which may be folded together with the mattress thereon with a minimum 15 of effort into a compact, vertically disposed form.

A still further object is to provide a bed suitable for use in articles of combination furniture such as described in my copending 20 applications, Serial Numbers 422,704 and 422,705, and also for use in mantel beds and the like.

According to the present invention, the bed comprises a vertically disposed head 25 frame suitably supported on the floor and adapted to receive a folded bed. The bed bottom is composed of a suitable number of sections adapted to fold upon one another into a condition of substantial equilibrium 30 about a pivot point movably connected to the head frame, about which point the folded bed body swings, the pivot point being movable to carry the bed into vertical position, and during which swing substantially the entire weight of the bed is supported on the 35 frame.

In the drawings which illustrate the invention:—

Fig. 1 is a side elevation of the open bed.

40 Fig. 2 is a partial plan view of same.

Fig. 3 is a side elevation of the bed partly closed.

Fig. 4 is a side elevation of the completely closed bed.

45 Fig. 5 is a plan view of the centre leg controlling link.

Fig. 6 is a fragmentary plan view of a corner of the head frame.

Fig. 7 is an enlarged cross section of one 50 side of the intermediate bed bottom section.

Referring more particularly to the drawings, A designates the head frame and B, C and D the head, foot and intermediate sections of a folding bed bottom. It will be understood that the bed bottom shown, which

comprises only three sections, is thus illustrated as a matter of convenience and that the number of sections comprising the bed bottom is not thereby limited. The exact construction of the bed bottom depends upon 60 the width or permissible height of the head frame and upon whether an end edge or a side edge of the bed bottom is presented to the head frame. The term "head frame" is purely arbitrary as, in the event of a bed 65 bottom presenting its side edge to the frame A, the frame would not be strictly speaking a head frame.

The head frame comprises corner uprights 11 connected to foot members 12 projecting in the longitudinal direction of the bed, both directly and by braces 13. The corner posts 11 are also connected at their lower ends by an angle or other suitable member 14 extending across the bed and at suitable intervals by 70 other transverse members 15. Braces 16 may be provided between the corner posts and the member 14. The construction thus described 75 constitutes a framework which will stand by itself on the floor and which will be sufficiently stable to support the bed in either open or closed position and during movement from one position to another. This frame 80 may be attached to some other article of furniture, such as a davenport, and be supported thereby or may be supported directly 85 from the floor, casters 17 being provided if desired to facilitate the movement of the device around a room. The free extremity of each member 12 preferably has the horizontal 90 outwardly turned flange thereof cut away, as shown in Figure 6, to give clearance for the legs of the device. The flange is obtained on the inside for the purpose of attaching a corner brace 16^a by securing a 95 short length of angle 12^a to the upstanding flange of the angle 12. The inturned flange of the angle 12^a and the outturned flange of the angle 12 provide horizontal surfaces to which the casters may be secured. At the 100 top of each corner post a member 18 may be connected extending in the longitudinal direction of the bed over the foot 12 and designed to support the top board of a davenport or the shelf of a mantel bed or 105 other element. Each member 18 may be rigidly connected to the frame by a brace 19. A short upright angle or the like 20 may be connected at a suitable point to each foot member 12 directly and by means of a brace 110

21. This member 20 will serve to attach the ends of a davenport frame to the bed frame A. It will be understood that the members 18, 19, 20 and 21 form no part of the invention or of the bed construction proper but are here shown and described merely as indicating the manner in which the bed may be incorporated in other articles of furniture.

10 The bed bottom sections B and C each comprise a U-shaped frame member 22 formed preferably of an angle iron bent to U-shape and provided at the corners with braces 23. The angles forming these frames are disposed with one flange inwardly turned 15 and one flange upwardly turned and the frames are arranged with their ends adjacent, as clearly shown.

20 The intermediate section comprises at each side of the bed a short length of angle 24 pivotally connected to the adjacent ends of the sections B and C at the points 25, the angle being disposed similarly to the angles of the frames 22 and the upwardly projecting flanges being connected. The whole 25 forms a rectangular framework in which any suitable form of bed bottom fabric may be stretched. A short length of angle 26 is disposed with one flange outwardly projecting and one flange downwardly projecting, the downwardly projecting flange being rigidly secured to the upwardly projecting flange of the intermediate section angle 24, so that the two angles together form a member of Z section, as 30 clearly shown in Figure 7. The length of the angles 26 is such that they form stops limiting the relative movement of the sections B, C and D in the folding up of the bed bottom, while the ends of the frames 40 22 projecting beyond the pivot points 25 form stops limiting the relative movement of the sections in the unfolding of the bed bottom.

45 The bed bottom is connected at each side to the head frame A by a link 27 which is pivoted at the lower end to the foot 12 and at the upper end approximately midway of the length of the head section B. This link is held against excess swing which 50 would lower the head end of the bed bottom by a leg 28 pivoted toward its upper end to the link. The upper end of each leg 28 is connected to the corresponding foot 12 by a link 29 pivoted at one end to the leg and at the 55 opposite end to the foot. The movement of the leg and link are controlled in the folding and unfolding of the bed by a jointed link 30 pivoted at one end to the leg 28 and link 29 at the junction thereof and pivoted 60 at the opposite end to the adjacent corner post 11. This jointed link 30 is provided with a tail 31, which forms a stop limiting the unfolding or straightening out movement of the link and through it the movement of 65 the members 28 and 29.

The extremities of the U frame in the head section B are provided with downwardly extending lugs 32, to which the upper ends of legs 33 are pivotally connected, the legs being connected across the bed bottom by any suitable number of straps 34, so as to form a comparatively rigid structure which serves as a transverse brace to hold the sides of the bed bottom frame against being drawn together by the tension of the bed bottom fabric. A separate transverse brace of any well known construction, indicated at 35, may be provided if desired, thus rendering possible the elimination of the transverse members 34. This leg is automatically operated in the folding and unfolding of the bed bottom by means of a link 36 at each side of the structure, pivotally connected at one end to the leg 33 and pivotally connected at the opposite end to the link 27 conveniently by means of a bracket 37 on the link 27. The legs 33 being positioned at the junction of the bed sections B and D, as clearly shown in Figure 1, support both sections in the open position. The links 36 at opposite sides of the bed are preferably connected by transverse members 38. It will be understood that the transverse members 34 and 38 are not essential but are desirable for the purpose of bracing the two sides of the bed and to ensure simultaneous and smooth action of the mechanism. The outer or foot end of the bed bottom section C is supported at each side by a leg 39 pivoted adjacent its upper end to a suitable point on the frame 22 and pivotally connected at its upper end with one end of a link 40, the opposite end of which is pivotally connected to the adjacent member 24 at a point eccentric with respect to the pivot 25 of the frame 22. The legs 39 may be connected across the bed by a transverse brace 41. The braces 34 and 41 may if desired be connected to the legs by diagonal braces 42, so that with the legs they will form a frame rigid in the transverse direction which will hold the bed against lateral swaying.

110 The operation of the device is extremely simple. Assuming the bed to be in the open position shown in Figure 1, the outer 115 end of the foot section C is lifted and the section swung through an angle of 90° until it is in vertical position. When it strikes the end of the stop member 26 on the section D and movement of the section C relative to the section D is thereby arrested and on continued movement of the section C, the pivotal motion is transferred to the connection of the sections D and B, so that as the section C swings down into parallelism with the section B, the section D swings to vertical position, as clearly illustrated in Figures 3 and 4. When this part 120 of the movement is complete, the section C is disposed above the section B and both 125 130

are in horizontal position and supported by the supports of section B. During the upward swing of section C, the links 40 swing the legs 39 into alignment with the bed section, as clearly shown in Figures 3 and 4, the movement being due to the differential action resulting from the eccentric disposition of the bed section and link pivots. On completion of the first folding movement, 10 the entire weight of the bed bottom is supported by the supports of section B. It will be noted that the upper end of the supporting link 27 is about midway of the length of section B, being in effect slightly 15 nearer section D than it is to the head of the section. This disposition of the supporting point places the folded bed bottom substantially in equilibrium, the greater portion overhanging toward the head frame. 20 A about balancing the lesser portion overhanging toward the foot with the additional weight of the intermediate section D and the legs 33 and their operating links 36. From the horizontal position, the folded bed 25 bottom swings with a touch to the inclined position shown in Figure 3, the side frames of section B finally coming to rest against the inturned flanges of the supporting links 27. During this movement, the links 36 30 draw up the legs 33 into parallelism with the side frames of section B in the same manner as the legs 39 are drawn up. In this position, the entire weight of the folded bed bottom and the mattress thereon is 35 supported through the links 27 on the head frame and on the legs 28. The folding operation is completed by pressing the folded bed bottom toward the head frame, which results in the supporting links 27 swinging 40 about their lower pivotal points on the head frame and bringing the parts into the position shown in Figure 4. In this final closing movement, the links 29 swing the legs 28 into alignment with the links 27, the 45 links 30 folding up.

The unfolding of the bed bottom is the reverse of the folding up operation, the only points of difference being that, when the folded bed is swung out to the inclined 50 position shown in Figure 3 and the legs 28 extended, their movement is limited by the tails 31 of the links striking the flanges of the head frame members 11. The employment of these folding links 30 enables 55 the links 29 to be quite light. If the links 30 were omitted, the links 29 would require to be sufficiently stiff to support the weight of the bed, as they would be in compression when acting to check outward movement of 60 the legs 28 and links 27. A second point of difference lies in the unfolding of the bed bottom proper. When the folded bed has been swung to horizontal position and the section C is being swung out, the extremities of the side members strike the members 65

24 after movement through an angle of 90° and cause the sections C and D to act as a single rigid member pivotally related to the section B. The legs 33 and 39 are obviously extended in the same manner as they are included during the folding up operation. 70

It will be obvious from the foregoing description that the bed may be folded up very easily as it is not necessary at any time to lift more than a small part of the weight 75 of the structure. When folded, the bed occupies a space slightly deeper than twice the thickness of the mattress and slightly higher than half the length of the bed and is thus readily available for concealment 80 in an article of furniture, such as a davenport, or for storage in a cupboard or behind a curtain suspended from the members 18. The construction employs only stock material and may be manufactured and put together with a minimum expenditure of 85 labor, so that the device will be inexpensive.

Having thus described my invention, what I claim is:—

1. In a folding bed, a main frame, a bed 90 bottom comprising a plurality of articulated sections, links pivotally connected to the frame and to the bed bottom and adapted to support the bed bottom in folded and unfolded position and to swing the folded 95 bed bottom into and out of the frame and legs adapted to limit the swing of the bed supporting links pivotally connected to the latter.

2. In a folding bed, a main frame, a foldable bed bottom, links pivotally connected to the frame and to the bed bottom and adapted to support the bed bottom in folded and unfolded position and to swing the folded bed bottom into and out of the frame, legs pivotally connected to the links and links connected between said legs and the frame to position the legs to limit of the bed supporting links. 105

3. In a folding bed, a main frame, a foldable bed bottom, links pivotally connected to the frame and to the bed bottom and adapted to support the bed bottom in folded and unfolded position and to swing the folded bed bottom into and out of the frame, legs pivoted to said links to limit the movement thereof and to support the bed bottom during unfolding and when unfolded, links connected between said legs and the frame to fold said legs upon the first named links 110 during the folding of the bed, and further links connected between said legs and the frame to limit the movement thereof and the movement of the first named links in unfolding the bed and to relieve said second 115 named links of load.

4. In a folding bed, a frame, a bed bottom comprising head, foot and intermediate articulated sections, links supporting said bed bottom and adapted to swing the same 120

in closed position into and out of the frame, said bed bottom being swingingly related to the links, legs connected to the head section of the bed bottom and adapted to support the same in horizontal position, additional legs pivoted to said links, and means operating automatically to extend said legs during movement of the section to horizontal position.

10 5. In a folding bed, a frame, a bed bottom, comprising a plurality of foldably connected sections, links pivotally connecting one of said sections to the frame, supporting legs foldably connected to certain of said sections, controlling connections extending between said links and the supporting legs of one of said sections, controlling connections extending between the bed bottom and the supporting legs of another of said sections, legs pivoted to said links, and controlling connections extending between said last mentioned legs and the frame.

6. In a folding bed, a main frame, a bed bottom comprising a plurality of articulated sections, links pivotally connected to the frame and the bed bottom adapted to swing the bed when folded to an inclined position, sufficiently far from the frame to permit the bed to swing about the links to horizontal position and legs pivoted to said links and means operable by movement of the links relative to the frame to swing said legs to folded and unfolded position.

7. In a folding bed, a main frame a bed bottom comprising a plurality of articulated sections, links pivotally connected to the

frame and to the bed bottom and adapted to swing the bed when folded to an inclined position sufficiently far from the frame to permit the bed to swing about the links to horizontal position and legs having pivotal connection with said links and adapted to support the bed bottom directly on the floor while it is being swung to horizontal position and unfolded.

45

8. In a folding bed, a main frame, a bed bottom comprising a plurality of articulated sections, links pivotally connected to the frame and bed bottom and adapted to support the bed bottom in folded and unfolded position and to swing the folded bed bottom into and out of the frame and means extending between the links and frame to limit the outward swing of the links and to assist the latter in supporting the weight of the bed bottom during folding and unfolding operations.

50

9. In a folding bed, a main frame, a bed bottom comprising a plurality of articulated sections, links pivotally connected to the frame and to the bed bottom and adapted to support the bed bottom in folded and unfolded position and to swing the folded bed bottom into and out of the frame and jointed connections extending between the links and frame adapted to limit the outward swing of the links during the initial unfolding of the bed bottom.

60

In witness whereof, I have hereunto set my hand.

RUDOLPH COOPERSMITH.
